GARMENT HANGER

Walter Rader, Milwaukee, Wis.; Myrtle Rader administratrix of said Walter Rader, deceased

Application May 20, 1936, Serial No. 80,795

1 Claim. (Cl. 223—98)

This invention appertains to apparel, and more particularly to garment hangers.

Garment hangers of the wire type are desirable from the standpoint of cheapness, but in actual use they are objectionable, due mainly to the fact that the wire hangers fail to hold the garment in its correct and desirable shape, the thin wire engaging the garment tending to crease the same, especially after a garment has been cleaned and pressed. Also, the danger of soiling the garment through rust and the like is ever present.

It is therefore one of the primary objects of my invention to provide a novel garment-supporting form, which can be readily and quickly associated with an ordinary wire hanger for covering the wire thereof, and for efficiently holding a garment, such as a coat, against creasing, and in the correct and desired shape after pressing and cleaning, the form also tending to naturally shape the shoulders and collar of a garment while the same is suspended from the hanger.

Another salient object of my invention is to provide a garment hanger attachment formed or pressed from a moulded material, the attachment or form being shaped to correspond to the natural configuration of the shoulders and neck of a person, whereby such shape will be imparted to the garment.

A further important object of my invention is the provision of novel means for forming the hanger attachment or form, whereby the attachment or form can be readily associated with or removed from a wire hanger, and in which accidental displacement of the form from the hanger is prevented.

A still further object of my invention is to provide a garment hanger attachment of the above character, which will be durable and efficient in use, one that will be simple and easy to manufacture, and one which can be placed upon the market at a reasonable cost.

With these and other objects in view, the invention consists in the novel construction, arrangement, and formation of parts, as will be herein-after more specifically described, claimed, and illustrated in the accompanying drawing, in which drawing:

Figure 1 is a front elevation of a wire garment hanger, with my improved attachment or form associated therewith.

Figure 2 is a top plan view of the same, with the shank of the hanger in cross section.

Figure 3 is a transverse section through the hanger and form taken substantially on the line

3—3 of Figure 1, looking in the direction of the arrows.

Figure 4 is a transverse section, taken substantially on the line 4—4 of Figure 1, illustrating the formation of the attachment or form at the ends of the shoulder support.

Referring to the drawing in detail, wherein similar reference characters designate corresponding parts throughout the several views, the letter A generally indicates my improved attachment or form for the garment hanger H. The garment hanger H forms no part of the present invention, but has been merely illustrated to show the use of my improved attachment or form A therewith. The hanger H is of the ordinary construction, and, as illustrated, is of the wire type and includes a stretcher bar 5 from the ends of which extend arms 6. These arms 6 converge upwardly and are joined above the center of the stretcher bar 5 to form a shank 7. One of the ends of the wire is continued above the other, and bent to form a hook 8, whereby the hanger can be suspended from a suitable support, such as a bar or hook.

My attachment or form A is shaped to conform to the natural configuration of a person's shoulders and neck, and thus the form will tend to impart such a shape to the garment, and hold the garment in its correct form after pressing. The attachment can be made from moulded fibrous material, or, if desired, the same can be pressed from sheet metal, or any other desired material. The unitary one-piece molded form A includes sloping shoulder supporting arms 10, which gradually flare outwardly toward their outer ends. These sloping shoulder supporting arms 10 are rounded, and curve downwardly at their ends, as at 11, to conform to the configuration of a garment, where the shoulder and sleeve portions of a garment meet. The arms 10 are integrally connected by a central collar-supporting portion 12, and the arms 10 and the collar-supporting portion 12 are connected by a rear wall 13.

To permit the ready association of the attachment or form A with a hanger, or the removal thereof, the central portion of the collar-supporting part 12 of the attachment is notched, as at 14, to receive the twisted shank 7 of the hanger H. To prevent accidental displacement of the attachment or form A from the hanger, the central collar-supporting part 12 of the attachment on each side of the notch 14 is provided with depending tabs or wings 15.

Obviously, to adjust the form or attachment on

the hanger, it is merely necessary to place the attachment over the hanger, with the shank 7 in the notch 14, and to then lower the attachment until it rests on the hanger, with the tabs 15 extending below the arms 6 of the hanger. To remove the attachment or form A from the hanger, it is merely necessary to raise the attachment until the tabs 15 are elevated above the hanger, at which time it can be lifted entirely off of the arms 6.

Due to the shape of the attachment or form, the garment is supported throughout a relatively wide area, and the wire of the hanger is completely covered. Hence, the creasing of the garment by the wire, after the garment has been freshly pressed, is entirely eliminated, and the form tends to hold the garment in its natural and preferred shape.

Changes in details may be made without departing from the spirit or the scope of my invention, but what I claim as new is:

A garment form adapted to be applied to a coat hanger including upwardly converging arms, and an upwardly extending shanked hook centrally of said arms, said forms comprising a one-piece molded hollow body adapted to be detachably fitted over said hanger, said body comprising upwardly converging shoulder supporting arms and a connecting collar supporting portion, said collar supporting portion being formed to provide a centrally disposed notch at one edge 10 thereof to receive the shank of said hook, said notch being of a size to surround said shank closely on three sides, and vertically depending wings on said edge of said collar portion on either side of said notch, said wings being adapted to 15 overlie said hanger arms in proximity thereto to maintain said shank against the back of said notch and prevent accidental displacement of said form from said hanger.

WALTER RADER. 20
